(57) **ABSTRACT**

A backlight control circuit includes LED circuits, a LED driver circuit, first switches and a switch module circuit. Each LED circuit includes a first and a second terminal. The second terminals of the LED circuits are connected. The LED driver circuit provides driving signals and dimming signal in sequence and provides error detection signals when the LED circuit is shorted or opened. The first switches are connected to the first terminals of the LED circuits for switching on or off the LED circuits based on the error detection signals. The switch module circuit includes second switches and third switches for timing provision of dimming signal. When a short or open circuit occurs, the error detection signal turns off corresponding first switch and third switch, so that the first terminal of the shorted/opened LED circuit is floating, and the second terminals can receive the dimming signal in other timing periods.

BACKLIGHT CONTROL CIRCUIT AND DRIVING METHOD THEREOF

RELATED APPLICATIONS

This application claims priority to Taiwan Application Serial Number 112148551, filed Dec. 13, 2023, which is herein incorporated by reference.

BACKGROUND

Technical Field

The present disclosure relates to a backlight control circuit and a driving method thereof, and more particularly to a backlight control circuit with a short-circuit and open-circuit detection mechanism and a driving method thereof.

Description of Related Art

Scanning driver chips, which are conventionally used to drive a light emitting diode (LED) display, usually include a row driver circuit and a column driver circuit. The row driver circuit provides control signals to each row of the LED display at different times, so that the column driver circuit can provide dimming data to the LEDs in each column in sequence and make the LEDs produce corresponding brightness according to the dimming data. For example, when the row driver circuit scans a certain row, the column driver circuit provides corresponding dimming data to all the columns corresponding to this row, so that the LEDs in all the columns corresponding to this row display the required brightness according to the dimming data.

In LED displays, one type of LED connection is the common cathode connection. In this connection manner, the anodes of the same column of LEDs are connected to different time-division driving signals, and the cathodes of the same column of LEDs are electrically connected to each other. Therefore, when a certain column of LEDs sequentially receive the time-division driving signals, these LEDs can receive the dimming data one by one in accordance with the time-division driving signals, thus displaying the required brightness. However, in the application of common cathode connection, when an LED in a certain region of a certain column is shorted or opened, because the cathodes are connected to each other, the light emitting behavior of other LEDs in the same column may be affected, thus failing to receive the correct dimming signals.

SUMMARY

Therefore, the present disclosure provides a backlight control circuit, which includes: a plurality of LED circuits, an LED driver circuit, a plurality of first switches, and a switch module circuit. The LED circuits are corresponding to a plurality of dimming zones in a one-to-one manner, each of the LED circuits includes a first terminal and a second terminal and the second terminals of the LED circuits are electrically connected to each other. The LED driver circuit is used to provide a driving signal and a corresponding dimming signal to each LED circuit according to timing, where when one of the LED circuits is shorted or opened, the LED driver circuit is further used to provide a corresponding error detection signal to each of the LED circuits. The first switches are electrically connected to the LED circuits and the LED driver circuit, where the first switches are separately electrically connected to the first terminals of the LED

circuits, so as to switch on or off the LED circuits according to the error detection signal corresponding to each LED circuit. The switch module circuit is electrically connected to the LED driver circuit and the second terminal of each LED circuit, so as to provide the corresponding dimming signal to each LED circuit. The switch module circuit includes a plurality of second switches and a plurality of third switches. The second switches are separately used to receive the driving signal corresponding to each LED circuit, for independent provision of the dimming signals at different times. The third switches, separately connected in series with a corresponding one of the second switches and used to receive the error detection signal corresponding to each LED circuit. When one of the LED circuits is shorted or opened, the error detection signal turns off the corresponding one of the first switches and the corresponding one of the third switches, so that the first terminal of the shorted or opened LED circuit has a floating voltage, the second terminal of the shorted or opened LED circuit is unable to receive the corresponding dimming signal, and other LED circuits with mutually connected second terminals receive the corresponding dimming signal.

According to an embodiment of the present disclosure, each of the LED circuits includes at least one LED.

According to an embodiment of the present disclosure, the first terminal of each LED circuit is an anode terminal of the at least one LED.

According to an embodiment of the present disclosure, the second terminal of each LED circuit is a cathode terminal of the at least one LED.

According to an embodiment of the present disclosure, the number of the second switches in the switch module circuit are equal to the number of the LED circuits.

According to an embodiment of the present disclosure, the number of the third switches in the switch module circuit are equal to the number of the LED circuits.

According to an embodiment of the present disclosure, when none of the LED circuits is shorted or opened, the first switches and the third switches corresponding to each of the LED circuits are normally turned on.

According to an embodiment of the present disclosure, each of the first switches comprises a control terminal, a first terminal and a second terminal, the control terminal is configured to receive the corresponding error detection signal, the first terminal is electrically connected to the LED driver circuit, the second terminal is electrically connected to the first terminal of corresponding one of the LED circuits.

According to an embodiment of the present disclosure, each of the second switches comprises a control terminal, a first terminal and a second terminal, the control terminal is configured to receive the driving signal, the first terminal is electrically connected to corresponding one of the third switches, the second terminal is electrically connected to the second terminal of the LED circuits.

According to an embodiment of the present disclosure, each of the third switches comprises a control terminal, a first terminal and a second terminal, the control terminal is configured to receive the corresponding error detection signal, the first terminal is configured to receive the corresponding dimming signal, the second terminal is electrically connected to the first terminal of corresponding one of the second switches.

The present disclosure further provides a driving method of a backlight control circuit, which includes: providing a driving signal to a first switch corresponding to each LED circuit according to timing; providing, by the second

switches of the switch module circuit, a corresponding dimming signal to a second terminal of each LED circuit; when at least one of the LED circuits is shorted or opened, performing the following steps: generating an error detection signal corresponding to the at least one of the LED circuits; and turning off the first switch corresponding to the at least one of the LED circuits and turning off a third switch corresponding to the at least one of the LED circuits in the switch module circuit according to the error detection signal; where after the first switch and the third switch corresponding to the at least one of the LED circuits are turned off, the first terminal of the at least one LED circuit has a floating voltage, the second terminal of the at least one of the LED circuits cannot receive the corresponding dimming signal, and other LED circuits with the mutually connected second terminals can receive the corresponding dimming signal.

According to an embodiment of the present disclosure, each of the LED circuits includes at least one LED.

According to an embodiment of the present disclosure, the first terminal of each LED circuit is an anode terminal of the at least one LED.

According to an embodiment of the present disclosure, the second terminal of each LED circuit is a cathode terminal of the at least one LED.

According to an embodiment of the present disclosure, the method further includes: when the LED circuits are normally sequentially driven, performing the following steps: turning on the first switch corresponding to each of the LED circuits, so that the driving signal is provided to the first terminal of each LED circuit according to timing; turning on a third switch corresponding to each of the LED circuits in the switch module circuit; and turning on a second switch corresponding to each of the LED circuits in the switch module circuit according to the timing, so that the corresponding dimming signals are provided to the mutually electrically connected second terminal of each of the LED circuits.

According to an embodiment of the present disclosure, the number of the second switches in the switch module circuit are equal to the number of the LED circuits.

According to an embodiment of the present disclosure, the number of the third switches in the switch module circuit are equal to the number of the LED circuits.

According to an embodiment of the present disclosure, each of the first switches comprises a control terminal, a first terminal and a second terminal, the control terminal is configured to receive the corresponding error detection signal, the first terminal is electrically connected to the LED driver circuit, the second terminal is electrically connected to the first terminal of corresponding one of the LED circuits.

According to an embodiment of the present disclosure, each of the second switches comprises a control terminal, a first terminal and a second terminal, the control terminal is configured to receive the driving signal, the first terminal is electrically connected to corresponding one of the third switches, the second terminal is electrically connected to the second terminal of the LED circuits.

According to an embodiment of the present disclosure, each of the third switches comprises a control terminal, a first terminal and a second terminal, the control terminal is configured to receive the corresponding error detection signal, the first terminal is configured to receive the corresponding dimming signal, the second terminal is electrically connected to the first terminal of corresponding one of the second switches.

BRIEF DESCRIPTION OF THE DRAWINGS

In order to make the foregoing and other objects, features, advantages and embodiments of the present disclosure more readily understandable, the accompanying drawings are described as follows:

FIG. 1 is a schematic diagram of a backlight control circuit according to an embodiment of the present disclosure;

FIG. 2 is a schematic diagram of a driving method of a backlight control circuit according to an embodiment of the present disclosure;

FIG. 3 is a schematic timing diagram of the driving method during normal operation of LED circuits according to an embodiment of the present disclosure;

FIG. 4 is a schematic circuit diagram in a control mode of the driving method in the case of a short circuit or open circuit according to an embodiment of the present disclosure;

FIG. 5 is a schematic timing diagram in a control mode of the driving method in the case of a short circuit or open circuit according to an embodiment of the present disclosure;

FIG. 6 is a schematic circuit diagram in a control mode of the driving method in the case of a short circuit or open circuit according to an embodiment of the present disclosure; and

FIG. 7 is a schematic timing diagram in a control mode of the driving method in the case of a short circuit or open circuit according to an embodiment of the present disclosure.

DETAILED DESCRIPTION

The following disclosure provides many different embodiments or examples for implementing different features of the provided disclosure. The embodiments of the components and configurations described below are merely illustrative and are not intended to be limitative. In addition, for purposes of simplicity and clarity, this disclosure repeats the reference symbols and/or numbers in the examples, and does not limit the relationships between the discussed various embodiments and/or components.

Referring to FIG. 1, FIG. 1 is a schematic diagram of a backlight control circuit 100 according to an embodiment of the present disclosure. The backlight control circuit 100 includes a plurality of LED circuits 110, an LED driver circuit 120, first switches Q₁~Q₄, and a switch module circuit 130. Each of the LED circuits 110 can be used independently as a dimming zone and display different brightness according to received dimming signal PWM_data. First terminals of the LED circuits 110 are SRC₁' to SRC₄' respectively, and their second terminals SNK' are electrically connected to each other. The LED driver circuit 120 is used to provide driving signals SRC₁~SRC₄ and a corresponding dimming signal PWM_data to each of the LED circuits 110 according to timing.

When one of the LED circuits 110 is shorted or opened, the LED driver circuit 120 is further used to provide corresponding error detection signals O/S_1~O/S_4 to the LED circuits 110 respectively. The first switches Q₁~Q₄ are separately electrically connected between each of the LED circuit 110 and the LED driver circuit 120, and are turned on or off according to the error detection signals O/S_1~O/S_4 corresponding to each of the LED circuit 110, thus control-

ling whether the first terminals SRC₁'~SRC₄' of the LED circuits 110 receive the corresponding driving signals SRC₁~SRC₄.

The switch module circuit 130 is electrically connected to the LED driver circuit 120 and each of the LED circuits 110, so as to receive the required dimming signal PWM_data from the LED driver circuit 120 and transmit it to the second terminal SNK' of the LED circuits 110 that are electrically connected to each other. The switch module circuit 130 includes second switches Q₅~Q₈ and third switches Q₉~Q₁₂, where the second switches Q₅~Q₈ are used to receive the driving signals SRC₁~SRC₄ corresponding to the LED circuits 110, and the third switches Q₉~Q₁₂ are used to receive the error detection signals O/S_1~O/S_4 corresponding to the LED circuits 110.

When one of the LED circuits 110 is shorted or opened, its corresponding error detection signal O/S_x turns off the corresponding one of the first switches Q₁~Q₄ and the corresponding one of the third switches Q₉~Q₁₂, so that the first terminal SRC_x' of this LED circuit 110 has a floating voltage and the second terminal SNK' of this LED circuit 110 cannot receive the corresponding dimming signal PWM_data. In this way, when one of the LED circuits 110 is shorted or opened, the backlight control circuit 100 of the present disclosure can enable other LED circuits 110 to receive normal dimming signal PWM_data even though their second terminals SNK' are mutually electrically connected, so that the brightness modulation of other LED circuits 110 is not affected.

Each of the LED circuits 110 includes one or more LEDs connected in series, and the first terminals SRC₁'~SRC₄' of the LED circuits 110 are the anode terminals of the LEDs, and the second terminals SNK' of the LED circuits 110 are the cathode terminals of the LEDs. In the embodiment of the present disclosure, a display region formed by the LED circuits 110 is a common cathode connection architecture. In addition, FIG. 1 illustrates only four LED circuits 110, but there may be more or less LED circuits 110 as required, the corresponding driving signals SRC_x, error detection signals O/S_x, and dimming signal PWM_data are provided, and the present disclosure is not limited thereto.

The LED driver circuit 120 is electrically connected to the first switches Q₁~Q₄ and the switch module circuit 130, and is used to provide driving signals SRC₁~SRC₄, error detection signals O/S_1~O/S_4, and dimming signal PWM_data thereto. The LED driver circuit 120 provides the driving signals SRC₁~SRC₄ to the first terminals of the first switches Q₁~Q₄ and control terminals of the second switches Q₅~Q₈ at different times, so that the driving signals SRC₁~SRC₄ can be transmitted to the first terminals SRC₁'~SRC₄' of the LED circuits 110 when the first switches Q₁~Q₄ are turned on and the second switches Q₅~Q₈ also can be sequentially turned on according to the driving signals SRC₁~SRC₄.

The LED driver circuit 120 provides dimming signal PWM_data to one terminal SNK of the switch module circuit 130, and transmits the corresponding dimming signal PWM_data to the second terminal SNK' of the LED circuit 110 through nodes N₁~N₄ when the switches in different columns of the switch module circuit 130 are turned on at different times. The LED driver circuit 120 is further used to provide the error detection signals O/S_1~O/S_4 to the control terminals of the first switches Q₁~Q₄ and the control terminals of the third switches Q₉~Q₁₂, such that the first switches Q₁~Q₄ and the third switches Q₉~Q₁₂ can be turned on or off according to the error detection signals O/S_1~O/S_4.

Specifically, when the LED circuit 110 is shorted or opened, the LED driver circuit 120 triggers its own internal short-circuit/open-circuit detection mechanism to cause state change (for example, the state is changed from logic 0 to logic 1 or from logic 1 to logic 0) of the error detection signals O/S_1~O/S_4, thus controlling the corresponding first switch (for example, at least one of the first switches Q₁~Q₄) and the third switch (for example, at least one of the third switches Q₉~Q₁₂) to be turned off. In this manner, the LED circuit 110 that is shorted or opened is prevented from receiving the driving signal and the dimming signal, without affecting other LED circuits 110. In some embodiments, the short circuit/open circuit detection mechanism may also be a detection circuit externally connected to the LED driver circuit 120, but the present disclosure is not limited thereto.

The switch module circuit 130 includes a plurality of columns of switches connected in parallel, and each column of switches include a second switch and a third switch connected in series. As shown in FIG. 1, the second switch Q₅ is connected in series with the third switch Q₉ to form a first switch column used for controlling the first one of the LED circuits 110; the second switch Q₆ is connected in series with the third switch Q₁₀ to form a second switch column used for controlling the second one of the LED circuits 110; the second switch Q₇ is connected in series with the third switch Q₁₁ to form a third switch column used for controlling the third one of the LED circuits 110; the second switch Q₈ is connected in series with the third switch Q₁₂ to form a fourth switch column for controlling the fourth one of the LED circuits 110.

In this embodiment, the number of the switch columns of the switch module circuit 130 depends on the number of the LED circuits 110. For example, if the number of the LED circuits 110 that require short-circuit or open-circuit detection is ten, the switch module circuit 130 has ten columns of switches, with one second switch in series connection with one third switch in each column. Thus, there will be a total of ten second switches and ten third switches in the switch module circuit 130.

Referring to FIG. 2, FIG. 2 is a schematic diagram of a driving method 200 of a backlight control circuit according to an embodiment of the present disclosure. The driving method 200 includes Steps 210 to 250, where Step 240 or 250 is selectively executed according to a determining result of Step 230. The driving method 200 of a backlight control circuit can be implemented by using the backlight control circuit 100 in FIG. 1 or architectures with similar functions, and the driving method 200 is described below with reference to the backlight control circuit 100 in FIG. 1.

In step 210, the LED driver circuit 120 provides driving signals SRC₁~SRC₄ to the first switches Q₁~Q₄ and the second switches Q₅~Q₈ of the LED circuits 110 according to timing, so that the first switches Q₁~Q₄ transmit the driving signals SRC₁~SRC₄ to the first terminals SRC₁'~SRC₄' of the LED circuit 110 according to timing, and the second switches Q₅~Q₈ are turned on one by one according to the timing of the driving signals SRC₁~SRC₄.

In step 220, the LED driver circuit 120 provides the corresponding dimming signal PWM_data to one terminal SNK of the switch module circuit 130 according to the timing, and when there is no short circuit or open circuit in these LED circuits 110, the dimming signal PWM_data can be normally transmitted to the mutually electrically connected second terminal SNK' of the LED circuits 110 in sequence.

In step 230, the LED driver circuit 120 detects whether each of the LED circuits 110 is shorted or opened (for

example, the first terminal SRC_x' of a certain LED circuit **110** is shorted to the second terminal SNK' , resulting in equal potential at the two terminals). When the LED driver circuit **120** detects that no LED circuit **110** is shorted or opened, step **240** of normally inputting the corresponding driving signals $SRC_1 \sim SRC_4$ and dimming signal PWM_data to the LED circuits **110** according to the timing is performed.

When the LED driver circuit **120** detects that one or more of the LED circuits **110** are shorted or opened, step **250** of using a control mode in the case of a short circuit or open circuit is performed. It should be understood that steps **210** to **230** are not performed necessarily in a certain order, and in fact the steps can be interchanged or varied. For example, step **220** may be first performed and then step **210** is performed, or the three steps are performed at the same time. Moreover, by performing Step **230**, the open-circuit or short-circuit situation of each of the LED circuits **110** can be detected throughout the whole process in real-time, but the present disclosure is not limited thereto.

When the LED driver circuit **120** detects that no LED circuit **110** is shorted or opened, step **240** is performed. In step **240**, first, sub-step **241** of turning on the first switch $Q_1 \sim Q_4$ corresponding to the LED circuits **110** according to the error detection signal $O/S\_1 \sim O/S\_4$ is performed, so that the driving signals $SRC_1 \sim SRC_4$ can be transmitted to the first terminals $SRC_1' \sim SRC_4'$ of the LED circuits **110** according to the timing. Specifically, because the LED driver circuit **120** detects that no LED circuit **110** is shorted or opened, the error detection signals $O/S\_1 \sim O/S\_4$ are not triggered to turn off the first switches $Q_1 \sim Q_4$ and thus the first switches $Q_1 \sim Q_4$ remain on; and the driving signals $SRC_1 \sim SRC_4$ are transmitted to the first terminals $SRC_1' \sim SRC_4'$ of the LED circuits **110** according to the timing.

In sub-step **242**, the LED driver circuit **120** turns on the third switches $Q_9 \sim Q_{12}$ corresponding to each of the LED circuits **110** in the switch module circuit **130** according to the error detection signals $O/S\_1 \sim O/S\_4$. Specifically, because the LED driver circuit **120** detects that no LED circuit **110** is shorted or opened, the error detection signals $O/S\_1 \sim O/S\_4$ are not triggered to turn off the third switches $Q_9 \sim Q_{12}$, and thus the third switches $Q_9 \sim Q_{12}$ remain on.

In sub-step **243**, because the first switches $Q_1 \sim Q_4$ and the third switches $Q_9 \sim Q_{12}$ are in the turned-on state, the first terminals $SRC_1' \sim SRC_4'$ of the LED circuits **110** and the control terminals of the second switches $Q_5 \sim Q_8$ are able to sequentially receive the driving signals $SRC_1 \sim SRC_4$ provided by the LED driver circuit **120**, so that the LED circuits **110** are sequentially driven and sequentially receive the required dimming signal PWM_data , thereby driving the LEDs in the LED circuit **110** to display corresponding brightness.

Referring to FIG. 3, FIG. 3 is a schematic timing diagram of the driving method **200** during normal operation of the LED circuits **110** according to an embodiment of the present disclosure. As shown in FIGS. 1 and 3, the LED driver circuit **120** provides the driving signals $SRC_1 \sim SRC_4$ at different times according to the timing $T_1 \sim T_4$. Because there is no short circuit or open circuit in each LED circuit **110**, the first switches $Q_1 \sim Q_4$ and the third switches $Q_9 \sim Q_{12}$ remain a normal on-state, so that the first terminals $SRC_1' \sim SRC_4'$ of the LED circuits **110** receive the driving signals $SRC_1 \sim SRC_4$ (i.e., $SRC_1' \sim SRC_4' = SRC_1 \sim SRC_4$). The second switches $Q_5 \sim Q_8$ are sequentially turned on according to the driving signals $SRC_1 \sim SRC_4$, such that the second terminal SNK' of the LED circuits **110** can receive the

dimming signal PWM_data input from the nodes $N_1 \sim N_4$ according to the timing $T_1 \sim T_4$.

Therefore, each of the LED circuit **110** is able to display corresponding brightness according to the driving signal and the dimming signal at corresponding timing. It should be understood that setting the dimming signal PWM_data of each LED circuit **110** in the drawing to 50% of dimming cycle is only an example, and in fact, the dimming signal PWM_data can be adjusted to different dimming cycles as required, so that the LED circuits **110** display the required brightness according to the dimming signal PWM_data . However, the present disclosure is not limited thereto.

The process goes back to step **230** of FIG. 2, in which step **250** is performed when the LED driver circuit **120** detects that there is an LED circuit **110** that has a short circuit or an open circuit. Step **250** includes sub-steps **251** and **252**. According to an error detection signal O/S_x output by the LED driver circuit **120** when detecting a short or open circuit in an LED circuit **110**, the first switch and the third switch corresponding to this LED circuit **110** are turned off. Therefore, the first terminal SRC_x' of this LED circuit **110** cannot receive the driving signal SRC_x (that is, the potential of the first terminal SRC_x' is a floating voltage), and the second terminal SNK' of this LED circuit **110** also cannot receive the corresponding dimming signal PWM_data during the corresponding timing. In this way, the shorted or opened LED circuit **110** may be independently turned off, so that other LED circuits **110** can also receive normal dimming signals PWM_data even though the second terminals SNK' are mutually electrically connected.

Referring to FIGS. 4 and 5 together, FIGS. 4 and 5 are respectively a schematic circuit diagram and a schematic timing diagram in a control mode of the driving method **200** in the case of a short circuit or open circuit according to an embodiment of the present disclosure. In the backlight control circuit **100** of FIG. 4, a short circuit occurs in the first one of the LED circuits **110** such that the potential of the first terminal SRC_1' of this LED circuit **110** is equal to the potential of the second terminal SNK' . In this case, the LED driver circuit **120** detects the short circuit in the first one of the LED circuits **110** and generates an error detection signal O/S_1 to the control terminals of the first switch Q_1 and the third switch Q_9 , so as to turn off the first switch Q_1 and the third switch Q_9 (FIG. 4 shows turn-off of the first switch Q_1 and the third switch Q_9 with the symbol X).

In this case, even if the second switch Q_5 is turned on by receiving the driving signal SRC_1 , the corresponding dimming signal PWM_data also cannot be transmitted to the second terminals SNK' of the LED circuits **110** that are electrically connected to each other. Moreover, the first terminal SRC_1' of the LED circuit **110** also cannot receive the driving signal SRC_1 due to turn-off of the first switch Q_1 , and presents a floating state. In other words, because the first terminal SRC_1' of the first one of the LED circuits **110** is in the floating state, the potential of the second terminal SNK' is unlikely to be pulled to the same level as that of the driving signal SRC_1 due to the short circuit. Thus, in other periods of timing, the potential of the second terminal SNK' will not follow the ground potential of the driving signal SRC_1 , so the dimming of other LED circuits still can be achieved.

As shown by the timing diagram of FIG. 5, when a short circuit occurs in the first one of the LED circuits **110**, the LED driver circuit **120** may still provide the driving signals $SRC_1 \sim SRC_4$ according to the timing $T_1 \sim T_4$, and triggers the error detection signal O/S_1 based on the detection result to turn off the first switch Q_1 and the third switch Q_9 . The

turn-off of the first switch Q_1 blocks the first terminal SRC_1' of the first one of the LED circuits **110** from receiving the driving signal SRC_1 (in the floating state), and the turn-off of the third switch Q_9 blocks the second terminal SNK' of the first one of the LED circuits **110** from receiving the corresponding dimming signal PWM_data at the timing T_1 .

In this case, even if the first terminal SRC_1' of the first one of the LED circuits **110** and the second terminals SNK' of the LED circuits **110** are equal due to a short circuit therebetween (i.e., $SNK'=SRC_1'=$ floating potential during the timing T_1), other LED circuits **110** are not affected during other periods of timing $T_2 \sim T_3$, only the first one of the LED circuits **110** fails to receive the driving voltage SRC_1 and the corresponding dimming signal PWM_data during the period of timing T_1 . In other words, the second terminals SNK' of the LED circuits **110** that are electrically connected to each other are unlikely to be electrically connected to the ground potential with the driving signal SRC_1 during other periods of timing $T_2 \sim T_3$ due to the short circuit in the first one of the LED circuits **110**, thus not affecting other LED circuits **110** to receive the corresponding dimming signal PWM_data .

It should be understood that other LED circuits **110** receiving the dimming signals PWM_data with 50% dimming cycle in their respective periods of timing $T_2 \sim T_3$ is only an example, and in fact, the dimming signal PWM_data can be adjusted to different dimming cycles as required, so that the LED circuits **110** display the required brightness according to the dimming signal PWM_data .

Referring to FIGS. 6 and 7 together, FIGS. 6 and 7 are respectively a schematic circuit diagram and a schematic timing diagram in a control mode of the driving method **200** in the case of a short circuit or open circuit according to an embodiment of the present disclosure. In the backlight control circuit **100** of FIG. 6, an open circuit occurs in the first one of the LED circuits **110**. In this case, the LED driver circuit **120** detects that the first one of the LED circuits **110** is opened and then generates an error detection signal O/S_1 to the control terminals of the first switch Q_1 and the third switch Q_9 , so as to turn off the first switch Q_1 and the third switch Q_9 (FIG. 6 shows turn-off of the first switch Q_1 and the third switch Q_9 with the symbol X).

In this case, even if the second switch Q_5 is turned on by receiving the driving signal SRC_1 , the corresponding dimming signal PWM_data also cannot be transmitted to the second terminals SNK' of the LED circuits **110** that are electrically connected to each other. Moreover, the first terminal SRC_1' of the LED circuit **110** also cannot receive the driving signal SRC_1 due to the turn-off of the first switch Q_1 , and presents a floating state.

As shown by the timing diagram of FIG. 7, when an open circuit occurs in the first one of the LED circuits **110**, the LED driver circuit **120** may still provide the driving signals $SRC_1 \sim SRC_4$ according to the timing $T_1 \sim T_4$, and triggers the error detection signal O/S_1 based on the detection result to turn off the first switch Q_1 and the third switch Q_9 . Therefore, during the period of timing T_1 , the node N_1 of the switch module circuit **130**, the second terminal SNK' of the LED circuit **110**, and the first terminal SRC_1' of the first one of the LED circuits **110** all present the floating state.

Specifically, the turn-off of the first switch Q_1 blocks the first terminal SRC_1' of the first one of the LED circuits **110** from receiving the driving voltage SRC_1 (in the floating state), and the turn-off of the third switch Q_9 blocks the second terminals SNK' of the LED circuits **110** from receiving the corresponding dimming signal PWM_data through the node N_1 , thus preventing other LED circuits **110** from being affected in other periods of timing $T_2 \sim T_3$.

It should be understood that other LED circuits **110** receiving the dimming signal PWM_data with 50% dimming cycle in their respective periods of timing $T_2 \sim T_3$ is only an example, and in fact, the dimming signal PWM_data can be adjusted to different dimming cycles as required, so that the LED circuits **110** display the required brightness according to the dimming signal PWM_data .

According to the backlight control module and its driving method of the present disclosure, by controlling the first switches electrically connected to the anode terminals of the LED circuits and the switch module circuit electrically connected to the common cathode terminals of the LED circuits, in the event of a short circuit or open circuit in at least one LED circuit, the light-emitting behavior of other LED circuits in the same column will not be affected in spite of mutual connection of the cathodes of the LED circuits. In this case, other LED circuits can still receive normal dimming signal according to the timing, thus implementing brightness adjustment.

The present disclosure has been disclosed above by preferred embodiments, and is not intended to limit the present disclosure. Any person with ordinary skill in the art can make some changes or modifications without departing from the spirit and scope of the present disclosure. Therefore, the protection scope of the present disclosure shall be subject to the scope defined by the appended claims.

What is claimed is:

1. A backlight control circuit, comprising:
a plurality of light emitting diode (LED) circuits, corresponding to a plurality of dimming zones in a one-to-one manner, wherein each of the LED circuits comprises a first terminal and a second terminal and the second terminal of each of the LED circuits are electrically connected to each other;

an LED driver circuit, used to provide a driving signal and a corresponding dimming signal to each of the LED circuits according to timing, wherein when one of the LED circuits is shorted or opened, the LED driver circuit is further used to provide a corresponding error detection signal to each of the LED circuits;

a plurality of first switches, electrically connected to the LED circuits and the LED driver circuit, wherein the first switches are separately electrically connected to the first terminal of each of the LED circuits, so as to switch on or off each of the LED circuits according to the corresponding error detection signal corresponding to each of the LED circuits; and

a switch module circuit, electrically connected to the LED driver circuit and the second terminal of each of the LED circuits, so as to provide the corresponding dimming signal to each of the LED circuits, wherein the switch module circuit comprises:

a plurality of second switches, separately used to receive the driving signal corresponding to each of the LED circuits so as to independently provide the corresponding dimming signal to each of the LED circuits at different times; and

a plurality of third switches, separately connected in series with a corresponding one of the second switches and used to receive the corresponding error detection signal corresponding to each of the LED circuits;

wherein when one of the LED circuits is shorted or opened, the corresponding error detection signal turns off the corresponding one of the first switches and the corresponding one of the third switches, so that the first terminal of the shorted or opened LED

11

circuit has a floating voltage, the second terminal of the shorted or opened LED circuit is unable to receive the corresponding dimming signal, and other LED circuits with mutually connected second terminal receive the corresponding dimming signal.

2. The backlight control circuit of claim 1, wherein each of the LED circuits comprises at least one LED.

3. The backlight control circuit of claim 2, wherein the first terminal of each of the LED circuits is an anode terminal of the at least one LED.

4. The backlight control circuit of claim 2, wherein the second terminal of each of the LED circuits is a cathode terminal of the at least one LED.

5. The backlight control circuit of claim 1, wherein the number of the second switches in the switch module circuit are equal to the number of the LED circuits.

6. The backlight control circuit of claim 1, wherein the number of the third switches in the switch module circuit are equal to the number of the LED circuits.

7. The backlight control circuit of claim 1, wherein when none of the LED circuits is shorted or opened, the first switches and the third switches corresponding to each of the LED circuits are normally turned on.

8. The backlight control circuit of claim 1, wherein each of the first switches comprises a control terminal, a first terminal and a second terminal, the control terminal is configured to receive the corresponding error detection signal, the first terminal is electrically connected to the LED driver circuit, the second terminal is electrically connected to the first terminal of corresponding one of the LED circuits.

9. The backlight control circuit of claim 1, wherein each of the second switches comprises a control terminal, a first terminal and a second terminal, the control terminal is configured to receive the driving signal, the first terminal is electrically connected to corresponding one of the third switches, the second terminal is electrically connected to the second terminal of the LED circuits.

10. The backlight control circuit of claim 9, wherein each of the third switches comprises a control terminal, a first terminal and a second terminal, the control terminal is configured to receive the corresponding error detection signal, the first terminal is configured to receive the corresponding dimming signal, the second terminal is electrically connected to the first terminal of corresponding one of the second switches.

11. A driving method of a backlight control circuit, comprising:

providing a driving signal to a first switch corresponding to each of a plurality of light emitting diode (LED) circuits according to timing;

providing a corresponding dimming signal to a second terminal of the LED circuits via a plurality of second switches in a switch module circuit according to the timing; and

when at least one of the LED circuits is shorted or opened, performing the following steps:

generating an error detection signal corresponding to the at least one of the LED circuits; and

turning off the first switch corresponding to the at least one of the LED circuits and turning off a third switch

12

corresponding to the at least one of the LED circuits in the switch module circuit according to the error detection signal;

wherein after the first switch and the third switch corresponding to the at least one of the LED circuits are turned off, a first terminal of the at least one of the LED circuits has a floating voltage, the second terminal of the LED circuits is unable to receive the corresponding dimming signal, and other LED circuits with the second terminal receives the corresponding dimming signal in other periods of the timing.

12. The driving method of claim 11, wherein each of the LED circuits comprises at least one LED.

13. The driving method of claim 12, wherein the first terminal of each of the LED circuits is an anode terminal of the at least one LED.

14. The driving method of claim 12, wherein the second terminal of each of the LED circuits is a cathode terminal of the at least one LED.

15. The driving method of claim 11, further comprising: when the LED circuits are normally sequentially driven, performing following steps:

turning on the first switch corresponding to each of the LED circuits, so that the driving signal is provided to the first terminal of each of the LED circuits according to the timing;

turning on the third switch corresponding to each of the LED circuits in the switch module circuit; and

turning on a second switch corresponding to each of the LED circuits in the switch module circuit according to the timing, so that the corresponding dimming signal are provided to the second terminal of each of the LED circuits.

16. The driving method of claim 11, wherein the number of the second switches in the switch module circuit are equal to the number of the LED circuits.

17. The driving method of claim 11, wherein the number of the third switches in the switch module circuit are equal to the number of the LED circuits.

18. The driving method of claim 11, wherein each of the first switches comprises a control terminal, a first terminal and a second terminal, the control terminal is configured to receive corresponding one of the error detection signal, the first terminal is electrically connected to a LED driver circuit, the second terminal is electrically connected to the first terminal of corresponding one of the LED circuits.

19. The driving method of claim 11, wherein each of the second switches comprises a control terminal, a first terminal and a second terminal, the control terminal is configured to receive the driving signal, the first terminal is electrically connected to corresponding one of the third switches, the second terminal is electrically connected to the second terminal of the LED circuits.

20. The driving method of claim 19, wherein each of the third switches comprises a control terminal, a first terminal and a second terminal, the control terminal is configured to receive corresponding one of the error detection signal, the first terminal is configured to receive the corresponding dimming signal, the second terminal is electrically connected to the first terminal of corresponding one of the second switches.
